Primary Examiner — Cynthia Ramirez*Assistant Examiner* — Llorellys Martinez-Rivera*(74) Attorney, Agent, or Firm* — Christensen O'Connor Johnson Kindness PLLC(57) **CLAIM**

The ornamental design for a lighting accessory for a portable electronic device, as shown and described.

DESCRIPTION

FIG. 1 is a front perspective view of a lighting accessory for a portable electronic device; FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right view thereof.

The broken lines illustrate portions of the lighting accessory for a portable electronic device which form no part of the claimed design.
